F. D. BARNES.

PARACHUTE GUN.

APPLICATION FILED SEPT. 23, 1908.

965,361.

Patented July 26, 1910.

UNITED STATES PATENT OFFICE.

FRED D. BARNES, OF MILWAUKEE, WISCONSIN.

PARACHUTE-GUN.

965,361.

Specification of Letters Patent. Patented July 26, 1910.

Application filed September 23, 1908. Serial No. 454,392.

To all whom it may concern:

Be it known that I, FRED D. BARNES, a citizen of the United States, residing in the city of Milwaukee, county of Milwaukee, 5 and State of Wisconsin, have invented certain new and useful Improvements in Parachute-Guns, of which the following is a specification.

This invention relates to improvements 10 in parachute guns and has among its salient objects to provide a construction in which a parachute is automatically shot or ejected from a cross-bow gun; to provide a novel construction of the parachute proper which 15 more effectively insures the opening of the latter during its descent; to provide novel details of construction and arrangement for setting the gun and for discharging the parachute; to provide a simple and reliable 20 device which can be readily and safely operated by a child and which can be manufactured at a low cost; and in general to provide an improved construction of the character referred to.

25 The invention consists in the matters hereinafter described and more particularly pointed out in the appended claim.

Referring to the drawings, Figure 1 shows a side elevation of my improved cross-bow gun, the set position of the gun being 30 shown in dotted lines. Fig. 2 is a fragmentary side elevation of the gun taken at right angles to the view shown in Fig. 1. Fig. 3 is a transverse sectional view taken 35 on lines 3—3 of Fig. 1 and looking in the direction of the arrows; Fig. 4 is a side view of the parachute in closed position, parts being broken away to reduce the size of the drawing. Fig. 5 is a similar view on 40 a smaller scale showing the parachute in open position. Fig. 6 is a sectional detail view showing the construction of the lower weighted end of the parachute. Fig. 7 is a fragmentary top plan view of the device 45 with the parachute arrow removed.

Referring to the drawings, 1 designates as a whole the barrel of the gun which consists essentially of a split metal tube comprising two halves, 2, 2', respectively. The 50 lower end of each of these halves, 2, 2', is secured to a wooden handle 3 by means of suitable screws or tacks 4, 4. The upper end of the parts 2, 2' telescope within and are secured to a tubular sleeve 5.

55 Upon each side of the sleeve 5 is mounted a bow-spring 7, each bow-spring consisting

in the preferred construction shown of a length of spring wire doubled back upon itself at its outer end, each half provided with one or more coils or turns 8 adjacent 60 to the side of the barrel and the terminal portion 8' inserted downwardly and fastened within a suitable socket 6. It will be understood that the two halves of each bow-spring are alike and extend substantially 65 parallel with each other throughout.

To the outer ends of the two springs is secured a bow-string, which preferably comprises sections of heavy rubber or elastic cord 9 at each end, and a middle portion of 70 non-elastic cord 10, which latter extends through the slot between the divided halves of the barrel. The lower edge of the sleeve 5 serves to arrest the outward movement of the bow-string and is suitably rounded to 75 prevent cutting the latter. The elasticity of the cord sections 9 is supplementary to the resiliency of the bow, and furthermore enables much shorter bow-springs to be used 80 than would be the case were the bow-string non-elastic.

In order to hold the bow in set position, the end of the handle or stock inside the tube or barrel carries a wire detent 11 secured to the stock by means of a stud or 85 bolt 12. The engaging end of this detent is desirably U-shaped and extends transversely of the slot between the halves of the barrel, as shown clearly in Fig. 2. When the bow is flexed the bow-string is hooked 90 over or beneath the detent 11. In order to fire the gun, a trigger 13 is provided, which takes the form of a bent lever pivoted about mid-length as at 14 between the ears of a bracket 15 suitably secured to the side of the 95 stock. The upper end of the trigger is bent to extend through an aperture 16 and through the U-shaped portion of the detent, while the opposite end of the lever normally stands obliquely outwardly away 100 from the stock, as indicated at 17. By pressing the exposed end of the trigger inwardly, the bow-spring is forced off from the detent and the bow released.

Describing, now, the parachute, designated as a whole 18, it comprises an arrow-like body 19, to the upper end of which is secured the cover or fabric 20, a slide-ring 21 mounted upon the arrow body and to which the lower ends of the stay-strings 22 110 are connected, and a notched member 23 upon the lower end of the arrow. The par-

achute fabric is desirably of light silk or analogous readily flexible fabric, and may be conveniently fastened to the upper end of the arrow by an encircling ring or band 5 24. The strings 22 may be simply tied onto the peripheral edges of the fabric at regular spaced apart intervals, and in order to limit the upward movement of the slide-ring, and thus hold the parachute in properly dis- 10 tended form, a stop 25 is provided on the side of the arrow at a suitable point. The notched member in the preferred embodiment shown consists of a soft or semi-soft rubber elongated cap, provided at its open 15 end with an inturned bead or constrictive part 26 which engages a suitable annular groove 27 in the end of the arrow, and so holds the cap attached thereto. Inside of the cap is provided a weight 28 which is 20 made just heavy enough to insure the prompt righting of the parachute after it has reached its maximum height after being shot, so as to insure the prompt opening of the device. The notched member 23 is also 25 provided with integral wings 29 which de- fine and form the notch in the butt end of the arrow. In using the gun, the bow is first set and the parachute arrow then in- 30 serted within the open end of the barrel, and adjusted so that the notch of the arrow straddles the bow string and rests upon the latter or detent. The length of the arrow below the lowest point to which the slide- 35 ring descends is desirably equal to, or slightly greater than, the length of the bar- rel from its discharge end to the detent, so that the slide-ring does not enter the barrel. The device is shot like an ordinary cross-bow, being usually, of course, directed 40 vertically upward.

As an improved detail of construction, I provide upon the discharge end of the barrel an outstanding prong 30 of suitable

length to enable the operator to place his toe upon the same when the end of the barrel is rested against the ground, thus enabling him to hold the gun down while he draws up the bow-string with both hands. It is thus optional to the operator whether he places the butt of the stock against his body and sets the bow by pulling the string toward him, or places the muzzle of the gun upon the ground, and holding it down with his toe, pulls the bow-string upwardly. 45

It will be understood from the foregoing 55 description that a device embodying my invention may be manufactured at low cost, that it is a toy which is peculiarly attractive and instructive to children, and that the several objects of the invention stated are 60 fully accomplished.

While the device herein shown constitutes a preferred embodiment of my invention, it is, of course, apparent that the details of construction may be varied without depart- 65 ing from the spirit of the invention.

I claim as my invention:

The combination with a parachute arrow, adapted to be shot from a gun of a collapsible automatically distending parachute 70 cover, mounted upon the head end of the arrow, a ring mounted to slide upon the body of the arrow, flexible cords, each secured at one end to the periphery of the parachute cover and at the opposite end to the ring, a 75 stop upon the body of the arrow between the slide ring and head end of the arrow and an elongated cap shaped forked notch mem- ber telescoped upon the butt end of the arrow and a weight within said notch 80 member.

FRED D. BARNES.
